UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO, CANADA.

SALES-CHECK HOLDER.

1,200,704.

Specification of Letters Patent. Patented Oct. 10, 1916.

Application filed January 10, 1912. Serial No. 670,486.

To all whom it may concern:

Be it known that I, EDWARD KIRBY BOTTLE, a citizen of the United States, residing at Elmira, in the county of Chemung and 5 State of New York, have invented certain new and useful Improvements in Sales-Check Holders, of which the following is a full, clear, and exact description, such as will enable others skilled in the art to which 10 it appertains to make and use the same.

The present invention relates to sales check holders, and has for its object to provide a simple and compact device of this character which will hold a number of 15 checks securely in position and is provided with a marking device for the checks so that the whole structure is self-contained and is cheap to manufacture. To this end I provide a box which is preferably rectangular and attach to one wall of the box a spring 20 plate containing a marking device. In the box I provide means consisting of strips of metal disposed parallel to a false bottom to the box so that the strips may be readily 25 placed between the leaves of a pad of checks and thus hold them in place after the box is locked, as is common in such devices.

In the accompanying drawing, wherein is shown one of various possible embodiments 30 of this invention, Figure 1 is a perspective sectional view of the complete device taken on the line Y—Y, Fig. 2. Fig. 2 is a sectional view taken on the line X—X, Fig. 1. Fig. 3 is a detailed view partially broken 35 away. Fig. 4 is a plan view of the complete device, showing the manner of punching the checks.

Similar reference characters refer to similar parts throughout the different views of 40 the drawing.

Referring now to the drawing in detail, 1 represents a rectangular receptacle, the four walls of which are preferably composed of a single folded piece of stamped sheet metal. 45 This receptacle is normally open at one side 2, which will be hereinafter referred to as the front, and is provided on the opposite or rear side with an opening 3, normally closed by a stop provided by a door 4 hinged 50 at 5 along its lower side to the bottom wall of the receptacle 1. A second piece of sheet metal 6 forms a support for the pad and constitutes a false bottom above the level of the hinge 5 whereby the pads may be easily 55 slipped in and out without engaging or

catching on the hinge. The upper edge of the door 4 is provided with a catch 7 engaging a recess 8 in the top wall of the casing, whereby the door is spring-locked in closed position. This lock may be released by 60 means of a key inserted in a keyhole 9, Fig. 3, at one side.

A member, as the spring plate 10, is secured to the top wall of the receptacle 65 in closes the locking mechanism and exerts a downward pressure upon the leaves of the pad or pads inserted in the receptacle. This pressure is merely sufficient to hold the pads 70 yieldingly against shifting movement within the receptacle and is not sufficiently great to interfere with the easy detachment of the sales checks. This plate is not intended to engage the top pad with sufficient pressure 75 to prevent its easy removal through the rear opening when desired.

In the embodiment of the invention herein shown, the receptacle contains three pads of sales checks denoted by the numerals 11, 12 and 13; the pads 11 and 12 being completely used, the stubs thereof only remaining while the pad 13, which is partially used, shows a plurality of checks 14. Each check is provided with two columns of numbers of any denomination suitable for the purpose for which the device 80 is intended. In lunch-rooms where a device of this character is most commonly used, these numbers are usually multiples of 5 and are punched by an ordinary round punch with the amount ordered. The person 85 pays the cashier the highest amount punched upon the check when leaving the lunch-room. Fraud may occur in a system of this general character as it is possible on obtaining one of the round punchings to replace it in the hole in the ticket or check, 90 so that it can hardly be distinguished except on a most careful examination, which permits a person to pay the next lowest amount punched. Fraud of this character is 95 avoided by this invention by attaching to the upper exterior surface of the receptacle a flat spring plate 15 by means of rivets or the like 16, and provided at its outer free edge with a V-shaped projection 17, and 100 downwardly projecting guides 18 at each side thereof engaging openings in the upper wall of the receptacle as shown in Fig. 3. As shown in Fig. 4, these act as stops or 105 gages to locate the check correctly. This 110

member 17 engages any one of the numbers along either side of the check 14 when the latter is detached and placed in the position shown in Fig. 4. The guides 18 limit the inward movement of the check, and then by pressing upon the spring plate 15, and pulling up upon the check, a V-shaped tear or mutilation 19 is made in the margin thereof opposite the number. The edges of this tear are more or less rough compared to the sharply defined edges of the usual round punching, so that it is practically impossible to replace these torn portions in the side of the check, thereby preventing the fraud described.

Connecting the interior side walls of the receptacle 1 are a plurality of pad stops, or plates 20, depending upon the number of pads used. These plates engage the stubs of the pad anywhere between the top and bottom leaves thereof when the pads are inserted through the rear opening 3. The binding of the pad herein shown by staples 21 will prevent the pad being drawn out through the front opening 2 after the door 4 is closed. In this manner the accidental loss of any of the pads, as might occur if their holding was dependent on the spring 10, and the chances of their falling into the hands of any people in the lunch-room are eliminated. A hook 22 is attached to one of the side exterior walls of the casing adapted to engage the belt of the waiter.

A convenient method of operating a device of this character is substantially as follows:— Consider the device to be attached to the belt of a waiter in the condition shown in Fig. 1, just before the rush hour. The operator realizes that the number of checks is insufficient, and in order to save time he goes to the manager or cashier, who unlocks the door 4 and removes the stubs of the pads 11 and 12, as well as the pad 13. The stubs 11 and 12 are used to check up previous transactions and the pad 13 is placed at the top of the receptacle formerly occupied by the pad 11, and two new pads are substituted for those removed and placed therebeneath. These pads, due to the false bottom formed by the plate 6, may be easily slipped in or out over the hinge 5, and the spring 10 exerts a gentle downward pressure thereon sufficient to prevent accidental removal or dropping out of the pads before the door 4 is closed. The device is then ready for use and is hooked to the belt of the waiter by means of the hook 22. Upon presenting a check after completing an order, the complete device is easily removed from the belt, the check 14 torn off and positioned beneath the projection 17 and it is held in place by the guides 18. The plate 15 is depressed by the thumb of the waiter and the check pulled up, which tears out the V-shaped clipping as shown in Fig. 4. The device is

then hooked to the belt again until a further check is desired. It is therefore quite clear that a device of this character is much easier to manipulate than those now in common use which require a separate punch. Thus it will be seen that this invention provides a practical and efficient device of the character above set forth, accomplishing among others, all the objects and advantages herein described.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. A device of the character described, comprising, in combination, a receptacle having oppositely disposed openings through one of which a pad comprising a plurality of connected leaves may enter the receptacle and through the other of which said pad may extend when in operative position, and means adapted to extend between adjacent leaves of the pad and prevent removal of the pad through said last mentioned opening.

2. A device of the character described, comprising, in combination, a receptacle having oppositely disposed openings through one of which a pad comprising a plurality of connected leaves may enter the receptacle and through the other of which said pad may extend when in operative position, means adapted to extend between adjacent leaves of the pad and prevent removal of the pad through said last mentioned opening, and a stop positioned transversely of the other opening.

3. A device of the character described, comprising, in combination, a receptacle having oppositely disposed openings through one of which a pad comprising a plurality of connected leaves may enter the receptacle and through the other of which said pad may extend when in operative position, means adapted to extend between adjacent leaves of the pad and prevent removal of the pad through said last mentioned opening, and a member adapted to yieldingly hold the pad against shifting in the receptacle.

4. A device of the character described, comprising, in combination, a receptacle having oppositely disposed openings through one of which a pad comprising a plurality of connected leaves may enter the receptacle and through the other of which said pad may extend when in operative position,

means adapted to extend between adjacent leaves of the pad and prevent removal of the pad through said last mentioned opening, and a pad supporting plate projecting 5 from the receptacle.

5. A device of the character described, comprising, in combination, a receptacle having oppositely disposed openings through one of which a pad comprising a plurality 10 of connected leaves may enter the receptacle and through the other of which said pad may extend when in operative position, means adapted to extend between adjacent leaves of the pad and prevent removal of 15 the pad through said last mentioned opening, a stop disposed transversely of the other opening, and a member adapted to yieldingly hold the pad against shifting in the receptacle.

20 6. A device of the character described, comprising, in combination, a receptacle having oppositely disposed openings through one of which a pad comprising a plurality of connected leaves may enter the receptacle 25 and through the other of which said pad may extend when in operative position, means adapted to extend between adjacent leaves of the pad and prevent removal of the pad through said last mentioned opening, a stop disposed transversely of the other 30 opening, and a pad supporting plate projecting from the receptacle.

7. A device of the character described, comprising, in combination, a receptacle having oppositely disposed openings through 35 one of which a pad comprising a plurality of connected leaves may enter the receptacle and through the other of which said pad may extend when in operative position, means adapted to extend between adjacent leaves of the pad and prevent removal of the pad through said last mentioned opening, a member adapted to yieldingly hold the pad against shifting in the receptacle, 45 and a pad supporting plate projecting from the receptacle.

8. A device of the character described, comprising, in combination, a receptacle having oppositely disposed openings through 50 one of which a pad comprising a plurality of connected leaves may enter the receptacle and through the other of which said pad may extend when in operative position, means adapted to extend between adjacent 55 leaves of the pad and prevent removal of the pad through said last mentioned opening, a stop disposed transversely of the other opening, a member adapted to yieldingly hold the pad against shifting in the receptacle, and a pad supporting plate projecting from the receptacle.

60 9. A device of the character described, comprising, in combination, a receptacle having oppositely disposed openings through 55 one of which a pad comprising a plurality

of connected leaves may enter the receptacle and through the other of which said pad may extend when in operative position, means adapted to extend between adjacent leaves of the pad and prevent removal of 70 the pad through said last mentioned opening, a spring plate connected to the receptacle adapted to yieldingly hold the pad against shifting therein, and a pad supporting plate disposed in the receptacle opposite said spring plate and projecting through the opening through which the pad is adapted to extend.

75 10. A device of the character described, comprising, in combination, a receptacle 80 having oppositely disposed openings through one of which a pad comprising a plurality of connected leaves may enter the receptacle and through the other of which said pad may extend when in operative position, 85 means adapted to extend between adjacent leaves of the pad and prevent removal of the pad through said last mentioned opening, a door hinged to the receptacle adapted to close the other opening, a spring plate 90 adapted to yieldingly hold the pad against shifting in the receptacle, and a pad supporting plate disposed in the receptacle opposite said spring plate and above said hinge and extending through the opening 95 from which the pad is adapted to extend.

11. A device of the character described, comprising, in combination, a receptacle having oppositely disposed openings to permit a pad to be introduced and disposed 100 with one end of the pad projecting from the receptacle, a stop adapted to prevent the withdrawal of the pad from one opening, and a door hinged to said receptacle and adapted to be disposed across said other 105 opening.

12. A device of the character described, comprising, in combination, a receptacle having oppositely disposed openings to permit a pad to be introduced and disposed 110 with one end projecting from the receptacle, a stop adapted to prevent the withdrawal of the pad from one opening, a door hinged to said receptacle and adapted to be disposed across said other opening, and a 115 false bottom adapted to support the pad above said hinge.

13. A device of the character described comprising, in combination, a receptacle having an opening adapted to receive a pad 120 of connected checks with the checks projecting through said opening, and a pad-stop connected to said receptacle and adapted to lie between checks of said pad.

14. In a device of the character described, 125 in combination, a receptacle open at opposite sides adapted to hold a pad, means engaging the pad between its top and bottom leaves adapted to prevent a removal thereof through one of the sides, and means 130

adapted to close the other side of said receptacle to normally prevent a removal of the pad through said opening.

15. In a device of the character described, in combination, a receptacle having an opening at one side thereof adapted to hold the stub of a pad, the leaves of said pad projecting through said opening, and means associated with the interior walls of said receptacle adapted to engage the pad between its top and bottom leaves to prevent a removal of the pad through said opening.

16. In a device of the character described, in combination, a receptacle having a plurality of openings, one of which is normally open and the other normally closed, said receptacle adapted to hold a pad, the leaves of which are bound together at one end, and means associated with the side walls of said receptacle adapted to be inserted between the leaves of said pad and engage the binding when said pad is inserted in the receptacle through the normally closed opening.

17. In a device of the character described, in combination, a rectangular receptacle open at opposite sides, a door normally clos-

ing one of said openings, and a plurality of transverse plates connected with the interior walls of the said receptacle each adapted to engage a pad between its top and bottom leaves to prevent a removal of the pad through the normally open opening.

18. In a device of the character described, in combination, a rectangular receptacle composed of a single piece of sheet metal having openings at opposite sides thereof, a door hinged to said receptacle normally closing one of said openings, means projecting through the opposite opening and adapted to support the leaves of a pad, and a plurality of plates adapted to engage a plurality of pads when inserted through the opening in the receptacle closed by said door to prevent a removal thereof through the opposite opening.

In testimony whereof I affix my signature, in the presence of two witnesses.

EDWARD KIRBY BOTTLE.
